UNITED STATES PATENT OFFICE.

JOHN POCHODZAJ, OF PAWTUCKET, RHODE ISLAND.

GARMENT-LOCK.

1,113,687.

Specification of Letters Patent. Patented Oct. 13, 1914.

Application filed April 8, 1914. Serial No. 830,408.

To all whom it may concern:

Be it known that I, JOHN POCHODZAJ, a subject of the Emperor of Austria-Hungary, residing at Pawtucket, in the county of Providence and State of Rhode Island, have invented certain new and useful Improvements in Garment-Locks, of which the following is a specification.

This invention relates to new and useful improvements in garment locks.

The primary object of this invention is to provide a lock for securing articles of wearing apparel to a permanent member and thereby preventing a loss of the same by theft.

A further object is to provide a lock adapted for engaging separate articles of apparel and simultaneously therewith engaging a permanent support whereby such articles are secured to the support and preventing any removal therefrom except by unlocking the lock with the authorized key.

A still further object is to provide a spring lock adapted for closing engagement with different articles of wearing apparel and a permanent support and whereby such articles are suspended from such support and are securely locked thereto.

With these general objects in view and others that will appear as the nature of the invention is better understood, the same consists in the novel combination and arrangement of parts hereinafter fully described, illustrated in the accompanying drawings and pointed out in the appended claims.

In the drawings forming a part of this application and in which like designating characters refer to corresponding parts throughout the several views: Figure 1 is an interior view of the lock illustrated in its closed position and with the front plate removed. Fig. 2 is a central longitudinal sectional view thereof illustrating two articles of wearing apparel suspended by the lock. Fig. 3 is a view similar to Fig. 1 but showing the lock in its open unlocked position. Fig. 4 is a transverse sectional view taken upon line IV—IV of Fig. 1. Fig. 5 is a transverse sectional view taken upon line V—V of Fig. 1. Fig. 6 is a transverse sectional view taken upon line VI—VI of Fig. 3. Fig. 7 is a front elevation of the lock in its closed position and suspended from a permanent support. Figs. 8, 9, 10, 11 and 12 are enlarged perspective views of the separate locking elements removed

from the locked casing. Fig. 13 is a perspective view of the lock casing with all of the mechanism and front plate removed therefrom. Fig. 14 is a perspective view of a portion of one of the garment supporting hooks. Fig. 15 is a perspective view of a portion of the garment supporting clasp and its pivotal connection with the casing, and Fig. 16 is a detail perspective view of the engaging toothed end of the garment clasp.

Referring more in detail to the drawings, the invention broadly consists of the lock 10 provided with a projectable bail 11 for suspending the lock from a ring or staple 12 upon a permanent support 13 for the purpose of locking garments to such support, such for instance as the hat portion 14 engaged by the clasp 15 and the coat portion 16 hung upon the locking hook 17.

The entire invention comprises a unitary structure of small dimensions and capable of being readily carried for convenient use in locking any desired garments to any member or support that may be desired.

The lock consists of a rectangular casing 18 having a front cover plate 19, while said plate is secured to the casing by means of the desired number of pins 20 projecting through perforations 21 of the plate and headed over or otherwise engageably secured at the front surface of the plate.

The bail 11 has an elongated end or extension 22 slidably mounted within the casing and flatly engaging one side 23 thereof. Said extension is provided with an open terminal slot 24 for slidably engaging over a block 25 rectangular in cross section and secured to the inner face of the back plate 26 of the casing while said extension is also provided with another slot 27 longitudinally positionable therethrough and slidably mounted upon the rectangular post 28 secured to said rear plate, which post 28 is provided with one of the aforesaid pins 20.

The bail slidably projects through the opening 29 in the casing end 30 while its free shorter end 31 is adapted for reception within the cut away portion 32 of the end wall 30, which cut away portion and the front plate 19 when positioned upon the casing provides a rectangular wall or keeper for said locking free end 31 of the bail.

The curved arm or clasp 15 is pivoted to the front plate 19 by the opposite lugs 33

mounted upon said plate at the edge thereof adapted to lie adjacent to the end wall 30 when positioned upon the casing and said clasp is provided with a notched extension 34 projecting inwardly of the casing through the slot 35 of the end wall whereby a swinging movement is imparted to said extension upon moving the clasp 15 upon its pivot. The said clasp is provided at its 10 free end with a foot 36 which has a plurality of prongs 37 mounted thereon and adapted to seat within sockets 38 formed in the front plate of the casing whereby an article of apparel such as the hat 14 is adapted to be pierced by said prongs and impinged between said foot 36 and the adjacent raised portion 39 of the front plate in which said raised portion the sockets 38 are provided.

A substantially rectangular tumbler 40 is 20 provided with a slot 41 for receiving an elongated post 42 mounted within the casing upon the rear wall thereof by which means the said tumbler is slidably mounted being normally positioned against the inner adjacent face 43 of the bail extension 22 when the elements are in their unlocked positions.

A block 44 is slidably mounted in the open sided slot 45 of the tumbler 40 and is provided with a shoulder 46 adapted to engage the adjacent inner wall 47 of a rectangular notch 48 in one side of the tumbler 40, while said wall 47 has an inwardly inclined portion 49 as best shown in Fig. 12.

A stem 50 upon the block 44 is provided 35 with an encircling helical spring 51' adapted to exert an inward impulse to the block and thereby maintaining the shoulder 46 in engagement with the tumbler 40 and also resiliently retaining said tumbler against said 40 extension face 43 when the lock is open. The clasp extension 34 is adapted for swinging movement in said notch 48 of the tumbler and is freely movable when the elements are unlocked. The bail extension is provided with a notch 51 and as best illustrated 45 in Fig. 1, the bail member when closed by forcing the same slidably inwardly, is positioned with the tumbler 40 engaging said notch 51 and thereby preventing any outward movement of the bail while simultaneously therewith, the inward end 52 of the block 44 is positioned beneath the clasp extension 34 and thus prevents any swinging movement of the clasp to its open position.

50 The hook 17 is secured to the rear wall 26 of the casing and is provided with a hinged or pivoted finger 53 and completing with said hook 17 a substantial circular inclosure around the adjacent casing wall, the said 55 finger being provided with a notched end 54 receivable within the slot 55 in the front wall 19 of the casing and thereby positioning the notch 56 of said finger end inclosed within the casing when the hook is in its closed position.

A lever 57 is pivoted to one of the pins 20 within the casing and is provided with a curved lower side portion 58 adapted to be engaged by the end 54 of the finger 53 when said finger is inserted interiorly of the casing while said side portion 58 of the lever 57 is adapted to seat within the notch 56 of said finger for locking the finger against being removed from the casing as illustrated in Fig. 1. A second or rear lever 59 is pivoted to another one of said pins 20 and extending in a direction toward the tumbler 40 is positioned with its reduced curved end 60 in constant engagement with the notch 61 of a corner extension 62 of said tumbler and whereby as will be evident from Fig. 1 of the drawings, any forcible movement of said rear lever 59 laterally will tend to shift the tumbler 40. A spring 63 encircling another one of said pins 20 is provided with one free end 64 engaging the front lever 57 and with its other free end 65 engaging the adjacent side face of the rear lever 59 and whereby both of said levers are resiliently influenced inwardly toward the locked positions as 90 illustrated in Fig. 1. The rear lever 59 is provided with a projecting finger 66 adapted to project within the line of pivotal movement of the front lever 57 and to thereby limit the inward swinging movement of 95 said front lever.

A key-hole slot 67 is provided through the rear wall of the casing and is adapted for the reception of the key 68. Said key is provided with a socket or bore 69 in its operative end adapted for seating over the pin 70 projecting inwardly from the front plate 19 of the casing and in alignment with the axis of the circular portion of the key-hole slot 67.

The side engaging block 71 of the key is 105 provided with a slot 72 which allows the block to pass over the stud 73 mounted upon the rear plate 26 of the casing and being for the purpose of preventing a manipulation of the lock by a false key unprovided with 110 such a slot.

With the locked elements positioned as illustrated in Fig. 1 and with the lock closed, the clasp being in engagement with the hat 14 and the hook 17 supporting the coat 16, 115 an unlocking of the bail, clasp and hook finger are simultaneously accomplished by the insertion of the key 68 in the key-hole slot 67 and a turning of the same in a direction indicated by the arrow in Fig. 3 whereupon 120 the elements assume their unlocked positions therein illustrated. This operation consists of an engagement of the edge of the key block 71 with the inclined side faces 74 and 75 of the front and rear levers respectively 125 whereupon both of said levers are moved outwardly, such movement being completed upon a seating of the key block upon the shoulders 76 and 77 respectively of the front and rear levers. Such a movement of 130

the front lever 57 disengages its lower portion 58 from the notch 56 of the finger end 54 thereby unlocking the coat 16 from the hook 17 by allowing a free pivotal movement 5 of the finger 53. Such movement of the rear lever 59 forces the upper tumbler engaging end thereof outwardly, thereby shifting the tumbler 40 out of its engageable position with the bail extension shoulder 51, thus 10 unlocking the bail, while such sliding movement of the tumbler removes the block portion 52 from beneath the enlarged extension 34 of the pivoted clasp 15 and thereby unlocks said clasp for the releasing of the hat 15 39 or other article in clasped engagement therewith.

It will be noted that with the elements in their unlocked positions as shown in Fig. 3, the key may be readily removed and the elements will remain in their said positions by reason of the engagement of the tumbler 40 with the bail extension face 43 and which engagement prevents the movement of the tumbler to its locked position. In using 25 the device, it is designed to first secure the bail to a permanent support by closing the same around such a member as the staple 12 whereupon the forcing of the bail inwardly releases the tumbler 40, which being projected by the spring 51' engages the shoulder 43 of the bail extension and thereby locks the device upon the permanent support as well as positioning the clasp and hook finger so as to be automatically retained 30 by the locked mechanism when thereafter closed either separately or simultaneously. With the bail in its closed position and the tumbler 40 positioned as shown in Fig. 1, it will be noted that upon closing 35 the finger 53, the notch 56 thereof will be retained by the resiliently positioned front lever 57, the side portion 58 of which seats within the notch, the lever being slightly swung outwardly against the force of the spring 64 by the engagement of the beveled corner 45 of the finger end 54 during its inward seating movement. Similarly, the extension 34 50 of the clasp 15 is provided with a beveled corner 81 which is positioned beneath the edge 52 of the spring pressed block 54, when the clasp is open and upon closing the same such corner 81 rides upwardly against the inclined face 83 of said block and thereby outwardly projecting said block against its 55 spring 51' and until the said extension moves above the plane of the block and whereupon the latter again assumes its seated position with its shoulder 46 engaging the portion 47 of the tumbler notch 48 and with the block 60 in its locking position beneath the clasp extension 34, it being noted that the inclined wall portion 49 of the tumbler accommodates the free swinging movement of the clasp extension and its engagement with the block 65 face 83 in its locking operation.

The complete operation of the device will be apparent from the above description, it being noted that with the elements in their unlocked positions and with the key removed, the clasp and hook are not operable 70 until after the bail has been closed but that after the closing of the bail and the consequent release of the tumbler, both the clasp and the hook finger are provided with automatic spring locking mechanisms and are 75 then readily employed for retaining any desired garments securely locked to the device, which device is already securely locked to a permanent support and all of which elements are releasable simultaneously by the 80 turning of the single key.

While the forms of the invention herein shown and described are what are believed to be preferable embodiments thereof, it is nevertheless to be understood that minor 85 changes may be made in the form, proportion and details of construction without departing from the spirit and scope of the invention as set forth in the appended claims.

What I claim is:—

1. A device of the class described comprising a casing, a bail slidably mounted within said casing, a clasp having an extension within said casing, a hook secured to said casing, a finger pivoted to said hook and having an end positionable within said casing, a tumbler within said casing adapted for locking engagement with said bail, a rear lever within said casing, and having its free end in constant engagement with said tumbler, a resiliently mounted block within said casing adapted for locking engagement with said clasp extension and a spring pressed lever within said casing adapted for locking engagement with said hook finger. 105

2. A device of the class described comprising a casing, a bail, an extension upon said bail slidably mounted within said casing and provided with a side notch, a slidable tumbler within said casing adapted for engaging said notch when said bail is in its closed position, a rear lever pivoted within said casing and having its free end in constant engagement with said tumbler, resilient means adapted for exerting an inward 110 influence to said lever, and a key adapted for imparting an outward movement to said lever. 115

3. A device of the class described comprising a casing, a bail, an extension upon said bail slidably mounted within said casing and provided with a side notch, a slidable tumbler within said casing adapted for engaging said notch when said bail is in its closed position, a rear lever pivoted within 120 said casing and having its free end in constant engagement with said tumbler, resilient means adapted for exerting an inward influence to said lever, said tumbler provided with a notch, a spring pressed block 125 130

normally projecting within said notch, a clasp pivoted to said casing and having a notched extension extending within said casing and adapted for depressing engagement with said block upon the closing of said clasp with the bail in its closed position.

4. A device of the class described comprising a casing, a bail, an extension upon said bail slidably mounted within said casing and provided with a side notch, a slidable tumbler within said casing adapted for engaging said notch when said bail is in its closed position, a rear lever pivoted within said casing and having its free end in constant engagement with said tumbler, resilient means adapted for exerting an inward influence to said lever, said tumbler provided with a notch, a spring pressed block normally projecting within said notch, a clasp pivoted to said casing and having a notched extension extending within said casing and adapted for depressing engagement with said block upon the closing of said clasp with the bail in its closed position, a hook secured to the rear of said casing, a finger pivoted to the free end of said hook and having its notched free end adapted for movement interiorly of the casing, a front lever pivoted within said casing and having its lower side portion adapted for seating

within the notch of said finger when said finger is in its closed position and resilient means engaging said front lever.

5. A device of the class described comprising a casing, a bail, an extension upon said bail slidably mounted within said casing and provided with a side notch, a slidable tumbler within said casing adapted for engaging said notch when said bail is in its closed position, a rear lever pivoted within said casing and having its free end in constant engagement with said tumbler, resilient means adapted for exerting an inward influence to said lever, a key adapted for imparting an outward movement to said lever, a hook secured to the rear of said casing, a finger pivoted to the free end of said hook and having its notched free end adapted for movement interiorly of the casing, a front lever pivoted within said casing and having its lower side portion adapted for seating within the notch of said finger when said finger is in its closed position and resilient means engaging said front lever.

In testimony whereof I affix my signature in presence of two witnesses.

JOHN POCHODZAJ.
